UNITED STATES PATENT OFFICE

ERNEST OLDENBUSCH, OF BROOKLYN, NEW YORK

HOLDER FOR GRAPHIC INSTRUMENTS

Application filed February 10, 1927. Serial No. 167,261.

This invention relates to holders for graphic instruments such as a fountain pen.

More particularly the invention relates to a holder connected with a base or stand for temporarily or releasably holding a fountain pen, or analogous instrument, in an angular position so that the instrument will be conveniently disposed; the holder being adapted for quick and easy removal of the instrument, 10 and for the insertion of one end thereof into the holder.

Some of the objects of the invention are:

The provision of a holder of the character mentioned which will accommodate graphic 15 instruments of various cross-sectional sizes; and to grip or clamp an instrument at two points in its length regardless of the cross-sectional size of the instrument.

The nature of the invention and its distinguishing features and advantages will appear when the following specification is read in conjunction with the accompanying drawing, in which

Figure 1 is a plan view of the holder of the 25 present invention arranged on a suitable base or stand;

Figure 2 is a transverse sectional view taken on the line 2—2 of Figure 1, and showing a fountain pen held in place by the 30 holder;

Figure 3 is a side elevation of the holder;

Figure 4 is a perspective view of one of the parts of the holder;

Figure 5 is a plan view of a spring forming a part of the holder;

Figure 6 is a perspective view of one of the parts of the holder.

The holder of the present invention will be mounted on a suitable base or stand which 40 may be of any preferred design and construction. The said base or stand is designated 10.

The holder is arranged on the base 10 and is adapted to releasably hold a graphic instrument such as a fountain pen 11 in an angular position. The base 10 is sufficiently heavy to maintain the fountain pen in an angular position when inserted into the holder.

50 The holder includes a tapered tubular

member 12, which constitutes a restricting means to restrict the insertion of one end of the fountain pen into the tubular member 12, but the extent of insertion of the end of the fountain pen is dependent upon the diameter of the end of the barrel of the pen. The fact that the tubular member 12 is tapered makes it possible to insert the end of the fountain pen regardless of the diameter of the end thereof and yet be securely gripped or clamped by the wall of the tubular member. The ink is thus kept from drying in the feed member of the pen.

The tubular member 12 is connected with a globular member 13 which is arranged on the small end of the tubular member. At the large end of the tubular member 12 there are arranged flexible gripping members 14. The gripping members 14 may be secured to the tubular member 12 in any preferred manner or may be formed integral therewith.

The outer free end of each of the gripping members 14 is curved outwardly as at 15 to facilitate the insertion of the end of the fountain pen. The gripping fingers 14 are adapted to grip or clamp the barrel of the fountain pen 11 and thus supplement the gripping action set up by the wall of the tubular member 12. It will therefore be understood that the fountain pen will be gripped at two points, namely, at the extreme end by the wall of the tubular member 12, and by the gripping fingers 14.

In the present instance, the tubular member 12 is supported for a universal movement, that is, movement up and down in a substantially vertical plane and movable around a vertical axis. This is accomplished by the use of a dome-shaped member 16, which is formed from a single piece of material and has an opening 17 therein which opens through the lower end of the member 16, and said member is also provided at its lower end with an outwardly directed flange 18. A disk 19 having an inwardly directed flange 20 is employed. The disk 19 is fixedly secured to the base 10 in any suitable manner. The member 16 is turnably associated with the disk 19 by virtue of the flange 18 on the member 16 and the flange 20 on the disk 19.

The globular member 13 is arranged within the member 16 with the tubular member 12 extending through the opening 17. A spring 21 is employed to set up the proper coaction 5 of the globular member 13 with the rounded top portion of the member 16. The spring 21 is in the form of a spider and is dished as at 22 to properly seat the globular member 13. It will now be understood that the tubular 10 member 12 may have pivotal movement up and down in a substantially vertical plane, and may also be moved around a substantially vertical axis.

A small piece 23 is put in place in the 15 lower portion of the opening 17 and is held against relative movement with respect to the member 16 by an upturned portion 24 arranged between the walls of the opening 17. The piece 23 rests on the flange 20. The 20 piece 23 is provided because it is easier to cut the opening 17 in member 16 through the lower edge of the member 16.

From the foregoing it will be understood 25 that a graphic instrument, such as a fountain pen, may have one end thereof readily inserted into the tubular member 12, regardless of the diameter of the end of the barrel which carries the feed member of the pen; that the said end of the pen will be gripped 30 by the wall of the tubular member; that the gripping members or fingers 14 will grip the barrel regardless of the diameter of the barrel so as to supplement the gripping action of the wall of the member 12; and that the 35 fountain pen will thus be steadily and releasably supported in an angular position.

It is to be understood that the invention is not restricted to the precise arrangement of parts shown and described, as the details of 40 construction may be modified and re-arranged without departing from the spirit of the invention, the scope of which is limited by the terms of the appended claims.

I claim:

45 1. A holder for a graphic instrument including restricted means for receiving and gripping and enclosing the writing end of the instrument, and flexible means for gripping the body of the instrument at a point beyond the restricted means.

50 2. A holder for a graphic instrument including a tapered tubular member for receiving and gripping and enclosing the writing end of the instrument, and flexible means 55 projecting from the receiving end of the tubular member for gripping the body of the instrument.

60 3. A holder for a graphic instrument including means for receiving and gripping 65 and enclosing the writing end of the instrument, and flexible members for gripping the body of the instrument.

65 4. A holder for a graphic instrument including a tapered tubular member for receiving and gripping and enclosing the writ-

ing end of the graphic instrument, and flexible fingers carried by the tubular member for gripping the body of the graphic instrument.

5. A holder for a graphic instrument including tubular means for receiving and gripping and enclosing the writing end of the instrument, and exterior flexible members on the tubular means for gripping the body of the instrument, each of said flexible members having a curved extremity to facilitate the insertion of the end of the graphic instrument into the tubular means. 70 75

6. The combination with a pen holding receptacle adapted to positively grip the writing end of a pen, of gripping means arranged exteriorly of the receptacle adapted to grip the barrel of said pen. 80

7. The combination with a pen holding receptacle adapted to positively grip the writing end of a pen, of gripping fingers arranged exteriorly on the receiving end of said receptacle adapted to grip the barrel of said pen. 85

8. The combination with a receptacle whose bore is tapered and thus adapted to receive and grip pen writing ends of different diameters, of gripping means arranged exteriorly on the receiving end of the receptacle for the purpose of gripping the pen barrels 90 95 of different diameters.
